(57) CLAIM

The ornamental design for an article of protective gear for the body, as shown and described.

DESCRIPTION

FIG. 1 is a front perspective view of an article of protective gear for the body showing my novel design.

FIG. 2 is a right side view article of protective gear for the body of FIG. 1.

FIG. 3 is a left side view article of protective gear for the body of FIG. 1.

FIG. 4 is a front view article of protective gear for the body of FIG. 1.

FIG. 5 is a rear view article of protective gear for the body of FIG. 1.

FIG. 6 is a top view article of protective gear for the body of FIG. 1; and,

FIG. 7 is a bottom view article of protective gear for the body of FIG. 1.

The broken lines are disclosed to show the inside environment of the article of protective gear for the body and form no part of the claimed design.
